US00D530010S

(12) **United States Design Patent** (10) **Patent No.:** **US D530,010 S**
Luettgen et al. (45) **Date of Patent:** **** Oct. 10, 2006**

(54) **BASE FOR AN ORAL IMPLEMENT**

(75) Inventors: **Harold A. Luettgen**, Windsor, CO (US); **Brian R. Williams**, Fort Collins, CO (US)

(73) Assignee: **Water Pik, Inc.**, Fort Collins, CO (US)

(**) Term: **14 Years**

(21) Appl. No.: **29/201,629**

(22) Filed: **Mar. 17, 2004**

(51) **LOC (8) Cl.** **24-02**

(52) **U.S. Cl.** **D24/152**

(58) **Field of Classification Search** D24/133, D24/152, 111, 217, 176; D13/107, 108; 320/250, 320/115; 601/162

See application file for complete search history.

(74) Attorney, Agent, or Firm—Dorsey & Whitney LLP

(57) **CLAIM**

The ornamental design for a base for an oral implement, as shown and described.

DESCRIPTION

FIG. 1 is a top perspective view of a base for an oral implement showing our new design;

FIG. 2 is a front elevation thereof;

FIG. 3 is a rear elevation thereof;

FIG. 4 is a left side elevation thereof;

FIG. 5 is a right side elevation thereof;

FIG. 6 is a top plan view thereof; and,

FIG. 7 is a bottom plan view thereof.

1 Claim, 4 Drawing Sheets
